UNITED STATES PATENT OFFICE.

CLIFFORD H. RAMSEY, OF GLEN ROCK, NEW JERSEY.

BREAKING ROLLER.

Application filed September 20, 1926. Serial No. 136,715.

This invention relates to the rollers or cylinders used in so-called button-breakers—machines having a number of rotated rollers in peripheral contact with which a fabric to be treated is extended in a bend around each of such rollers and in which, as the fabric is advanced through the machine, "buttons" or projections on the peripheries of the rollers act to flex the fabric and hence to render more supple the fibres thereof and to soften the same. These rollers have heretofore been formed by driving into the wooden body of the roller devices like upholstery tacks having mushroom shaped hollow heads or caps and slender shanks; the buttons formed by these devices work loose and fall out and their shanks sometimes break off and in time their heads wear away and break off, the detached buttons or broken-off heads or the projecting stubs of the shanks doing sometimes serious damage to the fabric, and sometimes, if the buttons are not fully driven in or they work out, crevices are left between the surface of the roller body and the button heads in which stray threads of the fabric catch, so that the fabric becomes damaged also in this way.

The present invention contemplates the provision of a studded roller for use, for example, in a button breaking machine which shall not be subject to any of these faults and the cost of which shall not be excessive.

35 In the drawing,

Fig. 1 is a transverse sectional view of the improved roller; and

40 Fig. 2 is a similar sectional view of a fragment thereof on a larger scale, a part appearing broken away.

45 1 is a cylindrical core composed of some suitably yielding material, such as wood; it is here shown as formed in sections, but that is not material. 2 is a shell which is fitted over this core. It is preferably formed of some relatively non-yielding substance, as a hard metal. The parts 1 and 2 form the body of the improved studded roller. I aim to support each stud or button against lateral displacement in the wood of the core as an incident of the wrenching action exerted thereon when in use and which is one cause of the buttons loosening and their shanks breaking off; this is the principal reason 50 for fitting and securing thereto a shell of relatively non-yielding material, as a hard

metal, which serves as a support for the studs as will appear. The shell is bored with holes 3.

The studs to afford the buttons are driven 60 through the holes into the wood of the core, being left projecting. (As a matter of actual practice holes to receive the studs, somewhat less in diameter than the studs, are previously formed in the core, which is 65 usually of hard wood.) Each stud fits the holes 3 through which it is driven, so that whereas it might otherwise be displaced laterally in the wood of the core it is fully supported against such displacement by the 70 relatively non-yielding material of the shell.

In the example illustrated the studs have heads in the form of enlargements thereon. One object of this is to provide them with acting or projecting portions of ample size 75 without having their entering portions of excessive diameter. 5 designates the shank of a stud and 6 its head, which is mainly rounded or convex but cylindrical at its base portion 6^a. If the studs are thus provided with such heads the holes 3 are enlarged or counterbored as at 4, so that when the studs are driven in their heads may stand countersunk in the shell 2 all around, one object of which is to sheath any laterally open crevice that would exist between any button head and the surface of the roller and in which threads of the fabric being treated might catch. 85

To anchor the studs in the roller I preferably form the shank 5 of each as a series of truncated cones 5^b having their major diameters adjoining the head of the stud, thus to form clinching shoulders 5^c; this is true except with respect to the topmost cone, between which and the head 6 a cylindrical neck portion 5^d is preferably left of a size to fit snugly the holes or bore 3. 90

Whereas the studs are firmly anchored in the wood against outward radial displacement by the radially outwardly facing shoulders 5^c, if they are formed with enlarged projecting portions or heads they will obtain as to such heads a solid seat on the hard non-yielding shell against inward radial displacement. The hard non-yielding shell also determines accurately the extent to which the studs may be driven in and if the stud heads are all formed of the same height the assembling of the studs with the 100 roller can be effected so that they will all form uniformly-high projections. 105 110

Usually the heads will not be mushroom-shaped or concavo-convex, as heretofore, but solid, as shown at the left in Fig. 2. Thus wearing away of any head leaves it always without the formation of an edge or burr to catch in or cut the fabric and it cannot by wear become detached bodily from the shank.

The heads are not only countersunk but fit snugly the counterbores 4, so that the hard non-yielding shell acts to support the heads themselves against lateral distortion. Since their base portions 6 do not conform to the general shape of the heads, but are cylindrical and of greater depth than the counterbores (in other words, since the holes have a snug fit around the studs at the periphery of the shell) no recesses exist to collect dye-stuff or other foreign matter which would soil or injure the fabrics, and since the shell is non-yielding they cannot be formed by any lateral pressing action of the studs.

Having thus fully described my invention what I claim and desire to secure by Letters Patent is:

1. A peripherally studded cloth finishing roller including a yielding core, a relatively non-yielding shell fitted thereover and having stud-receiving holes therein, and studs driven into the core through the holes and left projecting beyond the periphery of the shell and supported in the holes by the shell against lateral displacement.

2. A peripherally studded cloth finishing roller including a yielding core, a relatively non-yielding shell fitted thereover and having stud-receiving holes therein, and studs driven into the core through the holes and left projecting beyond the periphery of the shell, the outer portions of the studs being enlarged and seated against the shell and thereby supported against radially inward displacement.

3. A peripherally studded cloth finishing roller including a yielding core, a relatively non-yielding shell fitted thereover and having

stud-receiving holes therein, and studs driven into the core through the holes and left projecting beyond the periphery of the shell and supported in the holes by the shell against lateral displacement, the outer portions of the studs being enlarged and seated against the shell and thereby supported against radially inward displacement.

4. A peripherally studded cloth finishing roller including a yielding core, a relatively non-yielding shell fitted thereover and having stud-receiving holes therein, and studs driven into the core through the holes and left projecting beyond the periphery of the shell, said studs having clinching shoulders within and engaging the core and facing radially outward of the roller and also having their outer portions enlarged and seated against the shell and thereby supported against radially inward displacement.

5. A peripherally studded cloth finishing roller including a roller body and headed studs driven into the body and having their heads projecting from but countersunk in the peripheral surface of said body.

6. A peripherally studded cloth finishing roller including a yielding core, a relatively non-yielding shell fitted thereover and having stud-receiving holes therein and studs driven into the core through the holes and left projecting beyond the periphery of the shell, the projecting portions of the studs having heads fitting the holes and thereby supported against lateral distortion.

7. A peripherally studded cloth finishing roller including a yielding core, a relatively non-yielding shell fitted thereover and having stud-receiving holes therein and studs driven into the core through the holes and left projecting beyond the periphery of the shell, each hole having a snug fit around the corresponding stud at the periphery of the shell.

In testimony whereof I affix my signature.

CLIFFORD H. RAMSEY.
